[57] **ABSTRACT**

A movable contact structure for a large size electric switch which is arranged so the contacts of the switch may be readily inspected. The contact structure includes a movable contact retainer that has apertured ears and the base of the switch which supports the stationary contacts includes support posts, which, when the switch is disassembled to inspect the contacts, are available to act as a fulcrum for the shank of a screwdriver when the tip of the screwdriver is inserted into the apertures. The screwdriver thus may be used as a tool to overcome the spring forces holding the movable contact retainer and thus facilitate the removal and replacement of the movable contacts from its position on the movable contact carrier.

MOVABLE CONTACT STRUCTURE FOR AN ELECTRIC SWITCH

The present invention relates to switching devices and more particularly to the details of construction of a movable contact structure and support therefor in an electric switch.

The contact structure of the type with which the present invention is concerned is particularly suited for use in electromagnetic switching devices commonly known as contactors which are furnished as devices of varying sizes having ratings in accordance with the standards promulgated by the National Electrical Manufacturers Association, commonly known as NEMA. It is well known that any conductor is heated by the current passing through the conductor and therefore it follows that an increase in the current carrying capacity of a device requires a corresponding increase in the cross-sectional mass of the current carrying parts of the device. Thus in a device having a Size 5 NEMA rating, which is ascribed to an electric switch structure capable of controlling an electrical load of three hundred amperes or less, the movable contacts tend to become quite large. Inherently, any electrical switch which relies upon an abutting engagement between a stationary and a movable contact structure to complete an electric circuit will operate with a phenomenon known as contact bounce. Further, in any switching device the current conducting capacity between the stationary and the movable contact surfaces is dependent upon the area of surface contact and the pressure between the abutting surfaces. Thus as the size of the switches is progressively increased, the forces of the springs used in the movable contact structure must be progressively increased to minimize the contact bounce and maximize the current conducting capacity of the switch. Acceptable maintenance practices require that occasionally the contacts of the switches of the type with which the present invention is concerned be inspected for wear and that the contacts be replaced when necessary. In smaller size switches usually the replacement is accomplished with minimum difficulty. However, in larger sized devices, the forces exerted by the springs on the retainers, which maintain the movable contacts in their proper position, make the removal and replacement of the movable contacts difficult. The present invention relates to a movable contact retainer structure and a switch structure wherein the movable contacts may be readily inspected and removed and replaced without difficulty.

It is an object of the present invention to provide a movable contact retainer structure in an electric switch which will permit the contacts to be readily inspected and serviced.

An additional object is to provide an electric switch with a movable contact structure that includes a contact carrier having a portion movable in a slot in an insulating base and portions extending through openings in the base to a front surface of the base to provide a support surface whereon a movable contact is positioned and to connect the movable contact to the carrier by a spring biased retainer that has apertured ears and to provide the base with mounting posts which serve as a fulcrum for the shank of a screwdriver when the tip of the screwdriver is inserted in the apertured ears for the purpose of moving the retainer to a retracted position while the movable contact is removed or installed on the support surface.

Further objects and features of the invention will be readily apparent to those skilled in the art from the specification and appended drawing illustrating a preferred embodiment in which:

FIG. 1 is a perspective view of an electric switch incorporating a movable contact retainer structure according to the present invention.

FIG. 2 is a cross-sectional view of a base including the stationary and the movable contact structure of the switch in FIG. 1.

FIG. 3 is a perspective view of the movable contact and movable contact retainer shown in FIG. 2 with a portion of the movable contact support shown broken away.

For the convenience in description, the electromagnet switch or contactor is described herein as disposed in a

horizontal position when the contactor is mounted on a front wall of a vertical panel, the parts of the contactor being described in relation to this position. Accordingly, the terms front and rear, upper and lower, vertical and horizontal and the like are not absolute but merely define more readily the relative positions of portions of the parts and their relative positions to each other when the contactor is mounted on a panel.

Referring to the drawing, and particularly to FIG. 1, there is shown an electromagnetic switch assembly 10 having a plurality of components that are stacked one upon the other. The components of the assembly 10 include a metal mounting plate 12, an insulating base 14, and insulating barrier 16, a metal shock plate 18, an electromagnet assembly 20, a metal cover 22 and a movable contact carrier 24. The details of construction of the barrier 16 and the shock plate 18 are clearly set forth in an application for U.S. Pat., Ser. No. 99,613, concurrently filed herewith. The details of construction of the electromagnet assembly 20, as well as the arrangement for maintaining the electromagnet assembly 20 in the switch are disclosed in an application for patent having a Ser. No. 99,614, concurrently filed herewith. Similarly, the constructional details of the cover 22 and the arrangement for connecting the armature of the electromagnet assembly 20 to the movable contact carrier 24 are respectively shown in applications for U.S. Pat., Ser. Nos. 99,573 and 99,574, which similarly are concurrently filed herewith.

The mounting plate 12 is formed in a stamped metal part to provide a means to secure the switch assembly 10 to a vertical panel and the like, not shown. When the plate 12 is secured to the panel, an edge 26 becomes the bottom edge of the plate 12 and a surface 28 the front surface of the plate 12. The plate 12 has a pair of rearwardly extending indentations 30 along its bottom edge 26 that provide a pair of spaced mounting feet having openings therein. The plate 12 also has an indentation 31 at its top edge which provides an elongated mounting foot having an opening therein which, together with the indentations 30, are provided for the purpose of securing the plate 12 to a vertical panel.

The switch 10, as shown in FIG. 1, is a three pole device in that it is capable of completing and interrupting a three phase circuit when the switch 10 is actuated and deactivated. To enable the switch 10 to function as a three pole device, the base 14 is furnished with three sets of stationary contacts and movable contacts which are duplicates of the single set stationary contacts and the movable contact shown in FIG. 2. The base 14 and the barrier 16 are formed of a molded insulating material having arc suppressing capabilities and cooperate with each other to provide three compartments which extend in parallel between the top and the bottom of the switch 10. Positioned in each compartment is a set of stationary contacts and a movable contact. The base 14 has a rear surface 32 positioned on the plate 12 by suitable screws which pass through openings in the base 12 and are threadedly received in threaded inserts which are embedded in the material of the plate 12. Extending in the base 14 forwardly of the rear surface 32 and through the side walls of the base 14 is a slot 34. The slot 34 is centered in a centerline equidistant between a top wall 36 and a bottom wall 38 of the base 14 and is exposed to each of the compartments in the base 14 by a passage 40. Positioned on opposite sides of the passage 40 so as to be equidistant from a vertical plane through the center of the passage 40 is a pair of stationary contact assemblies 42 and 44 which are identical. Each of the assemblies 42 and 44 includes a terminal member 46 which is arranged to accept a bared end of a wire conductor, a conducting barlike member 48 and a support 50 for a noble metal piece that provides a stationary contact surface 52. The members 46 and 48 are positioned on a front wall 54 of the base 14 by a screw 56 which extends through openings in the member 46 and 48 into a threaded insert 58 which is embedded in the front wall 54. The support 50 is secured to the member 48 by a screw 60. The support 50 is shaped so the contact surface 52 is inclined and faces the vertical plane through the center of the passage 40.

For the convenience in description, the electromagnet switch or contactor is described herein as disposed in a

The movable contact carrier 24 is formed of a molded insulating material and is generally U-shaped, having a bight or body portion 64 received so as to be movable in the slot 34 and arm portions 66 extending externally of the side walls of the barrier 16. The arm portions 66 are connected to an armature 68 of the electromagnet assembly 20 and are moved rearwardly toward the plate 12 when the electromagnet is energized so that the bight portion 64 is moved rearwardly in the slot 34. A pair of compression springs 70 positioned between the rear wall of the bight portion 64 and the plate 12 position the bight portion 64 forwardly in the slot 34 when the electromagnet is deenergized. Extending through each of the passages 40 is a projection 72. The projections extend from the bight portion 64 to present a forwardly facing support surface 74 that is spaced forwardly of the front wall 54 of the base 14. Each projection 72 is rectangular in shape and has a rectangularly shaped cavity 76 extending from an open end at the rear wall of the bight portion 64 to a rearwardly facing spring seat 78 that is spaced rearwardly of the support surface 74. Extending through the material of the projection between the support surface 74 and the spring seat 78 are a pair of openings 80. The openings 80 are rectangular in shape and located along opposite sides of the surface 74 so the side walls 82 of the cavity in effect extend to the surface 74. If desired, a pair of spaced walls 84 extending parallel to the openings 80 may be provided to project from opposite sides of the projection 72 forwardly of the support surface 74.

Positioned on the support surface 74, when the electromagnet 20 is deenergized, is a movable contact 86. The movable contact 86 has a central portion 88 resting on the support surface 74 and a pair of arms 90 which extend generally in opposite directions from the central portion 88. The arms 90 are inclined and each has a noble metal portion secured thereon to present contact surfaces 92 which engage the contact surfaces 52 when the movable contact carrier 24 is moved rearwardly toward the plate 12 upon the energization of the electromagnet 20.

A means for removably positioning the movable contact 86 on the support surface 74 includes a U-shaped member 94, a metal part 96 and a spring 98. The U-shaped member 94 has a bight portion 100 resting on the central portion 88 and a pair of arms 102 extending from the bight portion along opposite sides of the central portion 88 through the openings 80 so that a portion 104 of the arms 102 is received within the cavity 76 in close proximity to the walls of the cavity 76. The walls of the cavity 76 and the openings 80 thus act as guides for the movement of the arms 102. Each portion 104 has a rectangular slot 106 therein. The slot 106 is located in the portions 104 to present a support portion 108 at the free ends of the arms 102. The metal part 96 has its opposite ends resting on the support portions 108 of the pair of arms 102 so a central portion on the part 96 provides a bridge between the free ends of the pair of arms and a seat 110 for an end of the spring 98 that has its opposite end resting against the spring seat 78. The spring 98 is thus positioned to urge the metal part 96 and the U-shaped part 94 rearwardly so that the bight portion 100 is constantly pressed into tight engagement with the central portion 88.

The movable contact 86 is further held against displacement from beneath the bight portion by a projection 112 which extends forwardly from the central portion into a centrally located opening in the bight portion 100. The energization of electromagnet assembly 20 causes the movable contact carrier 24 to move rearwardly to a position wherein the contact surfaces 92 engage the contact surfaces 52. When the carrier is at its furthest rearward position, the central portion 88 will be separated from the support surface 74 and the force provided by the spring 98 on the metal part 96 and the U-shaped part 94 on the central portion 88 will cause the contact surfaces 52 and 92 to be pressed into a firm engagement with each other.

Extending forwardly from the front wall 54 on the base 14 are four spaced posts 114 each of which has a front surface 116 whereon the shock plate 18 is mounted by four screws

118 in a manner illustrated in FIG. 1. The barrier 16, which is suspended from the shock plate 18 by four screws 120, as illustrated by FIG. 1, has its rear edge juxtaposed but not engaging the front wall 54 and includes rearwardly extending barriers which extend parallel to each other between the top and bottom of the barrier 16 so as to provide the three spaced compartments wherein the three movable and stationary contact assemblies of the switch 10 are received. The free ends of the arm portions 66 of the movable contact carrier 24 are secured to the armature 68 by a pair of screws 122 in a manner illustrated in FIG. 1. Thus access to the stationary and movable contacts of the switch 10 is readily obtained by removing the four screws 118 and the pair of screws 122 so that the assembly, including the shock plate 18, the barrier 16, the electromagnet assembly 20, as well as the cover 22, is removed as a unit from the base 14 while the movable contact carrier 24 remains assembled with the base 14. The removal of the shock plate 18 and the components assembled thereto will expose the front wall 54 and the stationary contacts assemblies 42 and 44 as well as the movable contacts 86 for inspection. The replacement of the stationary contacts is readily accomplished by removing the screws 60 and the supports 50 and substituting new supports 50 and replacing the screws 60.

The replacement of the movable contacts is facilitated by the presence of the mounting posts 114 and a pair of ears 124 that are formed to extend forwardly on the top and bottom edges of the bight portion 100. The ears 124 each have an aperture 126 therein. The apertures 126, together with the surfaces 116, provide a means whereby the force exerted by the springs 98 may be overcome and the bight portion 100 may be moved out of its engagement with the central portion 88. As illustrated by the broken lines in FIG. 2, the posts 114 provide a fulcrum for a shank of a tool, such as a screwdriver 128, which has its tip positioned in the aperture 126 in one of the ears 124. When the screwdriver 128 is thus positioned and a force applied, the U-shaped part 94 and the metal part 96 will move against the bias of the spring 98 and be temporarily held in a position wherein the bight portion 100 is spaced from the central portion 88 so the movable contact 86, which is to be replaced, may be slid from its position between the bight portion 100 and the surface 74 and a new movable contact 86 be installed in the position previously occupied by the removed removable contact 86.

The embodiments of the invention in which an exclusive property or privilege is claimed are defined as follows:

1. In an electric switch, the combination comprising: an insulating base having a front surface, a rear surface, a passage extending between the front surface and the rear surface and a pair of stationary contacts mounted on the front surface respectively equidistantly on opposite sides of the passage, an insulating movable contact carrier having a body portion movable in the passage and projecting through the passage to present a forwardly facing support surface that is spaced forwardly of the front surface, a cavity extending from a rear wall of the body portion into the projection and providing a rearwardly facing spring seat that is spaced rearwardly of the support surface, and a pair of openings in the support surface respectively extending along opposite sides of the surface into the cavity, a movable contact having a central portion positioned on the support surface, a pair of arms respectively extending from opposite sides of the central portion to present contact surfaces that are engageable with the stationary contacts when the body portion is moved to a predetermined position in the passage, and a means for removably positioning the central portion on the support surface including a U-shaped member having a bight portion engaging a front surface on the central portion, a pair of arms extending through the openings to present a portion on each arm within the cavity, and a slot in each arm portion within the cavity, a metal part having its opposite ends respectively extending into the slots and a central portion that provides a spring seat located between the arms and a spring having its opposite ends positioned on the spring seat in the cavity and the spring seat on the metal part

for constantly urging the bight portion against the central portion.

2. The combination as recited in claim 1 including at least one apertured ear forwardly extending from a side of the bight portion and at least one post forwardly extending on the base, said post providing a fulcrum for a shank of a screwdriver when a tip of the screwdriver is inserted in the aperture for the purpose of removing and installing the movable contact on the support surface.

3. The combination as recited in claim 1 wherein the cavity and the openings in the body portion have a rectangular shape so that the wall portions of the cavity and the openings provide guide surfaces for the arms of the U-shaped member when the U-shaped member is moved against the force provided by the spring.

4. The combination as recited in claim 2 wherein the cavity and the openings in the body portion have a rectangular shape so that the wall portions of the cavity and the openings provide guide surfaces for the arms of the U-shaped member when the U-shaped member is moved against the force provided by the spring.

5. The combination as recited in claim 1 including a pair of apertured ears respectively forwardly extending from opposite sides of the bight portion and a pair of posts forwardly extending on the base, said posts providing a fulcrum for a shank of a screwdriver when a tip of the screwdriver is inserted into one of the apertures for the purpose of removing and installing the movable contact on the support surface.

6. The combination as recited in claim 2 including at least one spring having an end engaging the body portion for urging the contact carrier to a position wherein the movable contact is separated from the stationary contacts.

7. The combination as recited in claim 2 wherein the contact carrier includes a main portion that is movable in a slot in a rear wall of the base, the body portion extends from the main portion through the passage and the cavity extends from a rear wall of the main portion into the body portion.

8. The combination as recited in claim 2 wherein the slots are elongated so that the metal part is movable between the arms of the U-shaped member.
